UNITED STATES PATENT OFFICE

118,929

DESIGN FOR A MOUNTING FOR A READING GLASS OR SIMILAR ARTICLE

Theodore Friedman, New York, N. Y.

Application September 12, 1939, Serial No. 87,155

Term of patent 7 years

To all whom it may concern:

Be it known that I, Theodore Friedman, a citizen of the United States, residing at New York, in the county of New York and State of New York, have invented a new, original, and ornamental Design for a Mounting for a Reading Glass or Similar Article, of which the following is a specification, reference being had to the accompanying drawing, forming part thereof, the figure being a perspective view of a mounting for a reading glass or similar article, showing my new design.

I claim:

The ornamental design for a mounting for a reading glass or similar article, as shown.

THEODORE FRIEDMAN.
